UNITED STATES PATENT OFFICE

2,476,710

WAX SLABBING APPARATUS

Charles F. Eaton, Methuen, Mass., assignor to
 Bennett Incorporated, Cambridge, Mass., a corporation of Massachusetts

Application November 9, 1945, Serial No. 627,594

5 Claims. (Cl. 18—26)

1

Slabs of wax are used in connection with machines of various types having rolls which, when the machine is in operation, need to be supplied constantly with a coating of wax. Waxes commonly used are paraffin and other compositions of similar nature having melting points in a range from a low of about 120° F. to a high of 200° F. Such wax is molded in the form of slabs which are adapted to be mounted in a holder so that one edge bears on the roll which is to be supplied with wax. Slabs provided for different uses may have different dimensions. One type commonly used has a length of 18 inches, a width of 12 inches and a thickness of about 1 1/4 inches.

The purpose of this invention is to enable slabs of the character above indicated to be produced more efficiently and at less cost than has been possible heretofore. A part of the object is to provide improved equipment which is both more efficient and less expensive to build, maintain and operate than equipment heretofore known. The invention comprises a combined apparatus in the use of which melted wax is delivered into molds, the molds and their contents are cooled in flowing water, and the slabs thus solidified are released and discharged from the molds. A preferred embodiment of the equipment used is shown in the accompanying drawings, in which,

Fig. 1 is a diagrammatic elevation of the apparatus;

Fig. 2 is a diagrammatic plan view of the apparatus;

Fig. 3 is a longitudinal sectional view of the tank in which the cooling step is carried out with a number of molds therein;

Fig. 4 is a plan view of the same;

Fig. 5 is a perspective view of one of the molds;

Fig. 6 is a vertical sectional view of the mold shown in Fig. 5;

Fig. 7 is a perspective fragmentary view of the bottom of the mold turned upside down;

Figs. 8 and 9 are fragmentary sectional views of parts of the tank and a mold taken on lines 8—8 and 9—9, respectively, of Fig. 3;

Fig. 10 is a rear elevation of the extractor by which cast slabs are released from the molds;

Fig. 11 is a vertical sectional view of the extractor shown in Fig. 10, taken on line 11—11;

Fig. 12 is a horizontal sectional view taken on line 12—12 of Fig. 10; and

Fig. 13 is a detail elevation of a holder for empty molds.

Like reference characters designate the same parts wherever they occur in all the figures.

The main parts of the apparatus and their

2

operative relationship to one another are shown diagrammatically by Figs. 1 and 2. These parts comprise a tank or kettle 1 of any suitable character, in which molten wax is contained, having a valve controlled outlet 2; a holder 3 in which molds 4 may be supported beneath the outlet 2 for filling; a tank 5 through which water is caused to flow continuously and in which the filled molds are placed to be chilled; and an extractor 6.

The tank or kettle may be of any suitable character, heated by any suitable means, and may either be the melting pot in which solid wax is melted or be supplied with melted wax from any other convenient source. The valve controlling its outlet may be of any character suitable for the purpose, preferably one which is capable of being opened and closed by single direct movements of the operator's hands. Both the tank outlet and mold holder are located near to the head end of the tank so that an operator standing by them can fill the molds one at a time, and place each mold when filled in the tank without shifting its position. In the arrangement here shown, the operator stands between the tank and mold holder and turns half way around to transfer molds from the holder to the tank.

The tank 5 is an elongated box and is shown in detail in Figs. 3 and 4. It has an inlet 10 for water at one end and an outlet 11 at the opposite end, (the outlet being located at the height at which it is desired to maintain the water level, such level being near the top edges of the tank walls), and is adapted to contain a series of molds and to support such molds in a manner permitting their movement lengthwise from the front or head end to the rear end of the tank. A mold pusher 12, hereinafter described, is mounted in the front or receiving end of the tank and, preferably, a thermometer 13 is mounted in a suitable location in or near the rear end to show the temperature of the water in the region of the tank from which the molds are removed.

The mold which I prefer to use, and which embodies novel features, is illustrated in Figs. 5—9 inclusive. It consists of a mold proper 14 made of material which is a good conductor of heat, preferably sheet metal, and has internal dimensions suited to the slabs to be produced. Its walls are slightly tapered, with the greatest distance between them at the open end of the mold to permit easy withdrawal of the cast slab. Flanges 15 and 16 are united to the opposite sides of the mold at the top end and extend outwardly at 55 substantially right angles to the median plane

of the molding space. A tapered pin 17 is mounted in the flange 15 projecting downwardly therefrom, and a hole 18 is provided in the flange 16; such pin and hole being in the same vertical plane perpendicular to the width dimension of the mold chamber. The pin is adapted to enter a hole like the hole 18 in the flange of a similar mold at one side, and the hole 18 is adapted to receive the pin of a similar mold at the other side, of the mold here shown.

On the intermediate sides of the mold and at the ends of the flanges 15 and 16 are upwardly extending (and preferably outwardly inclined) wings 19 terminating in lips 20 which are spaced from one another by a distance about equal to the width of the tank and are adapted to rest on the upper edges of the side walls of the tank whereby to suspend the mold in the manner shown in Fig. 3. As thus suspended, the molds are immersed in the cooling water as to all of their height except the open upper end, and their external surfaces are in direct contact with the water. The side walls of the tank are armored with angle irons 21 at their upper edges to provide wear resisting and relatively frictionless tracks on which the lips 20 of the molds may rest and slide. Strips 22 are secured to the lateral flanges of the respective angle irons with a spacer bar 23 between each strip and the underlying flange; and are located to overlie the mold lips 20, forming guard rails for preventing lifting of the molds by upward force components resulting from pressure applied to the endmost mold in forcing a long series of molds toward the rear end of the tank. These guard rails terminate short of both ends of the tank by distances enough longer than the lips 20 to permit insertion of molds at one end and removal of the molds at the opposite end of the tank.

Spacers 24 are secured to the broad sides of the mold at different levels. In the illustrated embodiment the spacers are angular strips of sheet metal suitably secured, as by soldering, to the walls of the mold and are pierced by a sufficient number of large holes 25 to permit free flow of water into and out of the spaces embraced between the spacers and the walls of the mold. Corresponding spacer projections on both sides of all molds are at equal distances from the top of the mold, and all project a distance equal to half the prescribed spacing between adjacent molds in the tank, whereby to maintain the molds parallel to one another when suspended in the tank in the manner shown in Fig. 3 and while being advanced by pressure applied to the endmost mold.

The bottom wall 26 (Fig. 7) contains a vent hole 27, the purpose of which is to admit air when the mold is turned upside down and the casting therein released from adherent connection with the mold walls. This vent may be closed by a tapered plug 28, which is carried by a resilient arm connected to the wall 26 by a pivot 30. The vent hole and plug are equidistant from the pivot and the arm can be swung so as to bring the plug into register with the hole or place it at one side thereof. When in register, the resilience of the arm causes the plug to enter and stop the hole, preventing the wax from running out while the mold is being filled.

The pusher 12 previously mentioned comprises a handle bar connected to two arms 31, which are pivoted to brackets 32 on the bottom of the tank adjacent to the side walls, and a presser bar 33 connected by short arms 34 and pivots 35 with the arms 31. The presser bar is offset rearwardly and

is located at a height such that it may engage the side, near the upper end, of the nearest mold suspended from the tank walls as previously described; and the amplitude of swinging movement permitted to the pusher is greater than the spacing of the assembled molds from one another. The approximate limits of swinging motion are indicated by full and dotted lines in Fig. 3. Stop shoulders are provided on the arms 10 34 engaging arms 31, as illustrated by Fig. 3, to hold the presser bar 33 in the desired offset position.

Near the rear end of the tank, the side walls are formed with a downward jog or shoulder indicated by dotted lines at 36, and between this jog or shoulder and the rear end wall, the side walls have upper edges 37 at a lower level than the angle irons 21. The difference of level is somewhat greater than the length of the locking pin 17, enough so to permit the rearmost mold to drop clear of the pin on the next mold when it passes beyond the shoulders; and the horizontal distance between the shoulder 36 and adjacent end of the tank is greater than the over all distance between the outer edges of the flanges 15 and 16, so that the endmost mold, after dropping, may be shifted by the operator clear of the next following mold, and then lifted out of the tank.

The extractor 6 (Figs. 10, 11 and 12) is an enclosed box or chest having an opening 38 in its bottom and being supported on legs or a frame 40 at a height convenient to permit an operator to pass molds singly, upside down, through the opening. Bars 41 and 42 are mounted in the box close to the bottom thereof extending across the ends of the opening from front to rear. They are connected with the box bottom by pivots 43 and 44 in locations permitting them to be brought 30 near enough together to support the lips 20 of any mold, as shown by full lines in Fig. 12, and to be swung apart more widely than the distance between the outer edges of the opposite lips, as shown by broken lines, whereby to release the 35 mold and permit it to fall. Pivot 43 is near the front of the box and pivot 44 near its rear, and the two bars are connected by a linkage consisting of a lever 45 having unequal arms pivoted at 46 to the bottom of the box, between the before named bars, a link 47 connecting arm 41 with the short arm of lever 45, and a link 48 connecting the long arm of said lever with the arm 42. The ratio of long to short arms of lever 45 preferably is substantially equal to that between 40 the distance from pivot 44 to the point at which link 48 is connected to bar 42 and the distance from pivot 43 to the point of connection of link 47 with bar 41, so that the bars will turn through equal angles. A limit bar 49 is connected with the 45 arm 41 by a pin and slot connection 50 and with the arm 49 by a pin and slot connection 51. Its function is to limit the swinging movement of the arms to approximately the extreme positions indicated in the drawing. The pins of these connections may be adjustable lengthwise of the arms, whereby to vary the limits of their swinging movements. The arms and levers are supported clear of the chest bottom by spacer disks 52 underneath their fulcrum portions and supporting tracks 53 at locations remote from their pivots. Arm 41 has a handle portion 54 protruding from the rear wall of the box or chest.

A centering bar 55 extends from side to side of the extractor box midway between the front 55 and rear walls thereof and has an elongated

notch 56 in its under side located to receive the inverted bottom of the mold when the mold is inserted and lifted clear of the supporting bars. Heating means are located in the extractor chamber comprising a serpentine steam pipe 51, the bends of which are disposed to embrace the space wherein the mold is received, and a nozzle 58 directed toward that space in the lower part of the chamber. Valves 59 and 60 control admission of steam to the pipe 57 and nozzle 58, respectively, and pipe 51 discharges into a steam trap 61. A thermometer 62 is preferably mounted on the chamber to indicate the temperature therein.

Beneath the opening 38 a switch member 63 is pivoted to the supporting framework by a pivot rod 64 parallel to the long dimension of the opening 38 and vertically beneath the median line of the opening. This switch is a board or plate having greater mass above than below the pivot axis, whereby gravity tends to hold it in either of two extreme positions. It is stopped in the position shown by full lines in Fig. 11 by engagement of its lower edge with a ramp 65, and in the opposite extreme position indicated by broken lines at 63a by engagement with a ramp 66. The extent and weight of the part of the switch member below the pivot 64 and the position of the ramp 65 are designed with such values in reference to the length and weight of a slab of wax that, when such a slab falls from the mold and is deflected by the switch to the ramp, its rearmost end in bearing on the switch below the pivot will cause the switch to swing beyond its dead point. Successive positions of a slab leaving the mold are shown by broken lines at s', s², s³ and s⁴. In passing from position s³ to s⁴, the slab bears on the lower arm of the switch and swings the latter to the broken line position 63b, whence it continues by gravity to the extreme position 63a.

Release of wax slabs from their molds is accomplished by heat. A constant heating effect is maintained by the pipe 57, and when each mold is inserted into the chamber, the valve 60 is opened to deliver a jet of live steam against the mold. Then the heat softens the surfaces of the slab enough to release its bond with the mold, whereupon the slab falls out by gravity; the vent hole 27 being then open, and the widening taper of the mold walls leaving the slab free to emerge. It then travels the course previously described. Slabs may be allowed to slide from the ramp 65 to a depository, not here shown, or may be arrested by a lip 67 of the ramp and be thereafter removed by an attendant.

The empty mold is then released by action of the operator in moving the handle 54, and thereby the arms 41 and 42, to the position shown by broken lines in Fig. 12, whereupon the mold falls and is deflected by the switch to the ramp 66. As its inverted bottom end bears on the portion of the switch below the pivot 44, it tips the switch back to the first position.

It is important that the molds be free from water internally when being filled, and I have provided a holder for supporting them to dry after being discharged from the extractor chamber. Such a holder is shown in Fig. 13 and has a base 68 with uprights 69 at opposite ends having lateral arms 70 and 71. The arms at the two ends of the holder are spaced apart correspondingly to the spacing between the lips 20 of the individual molds and each arm is somewhat longer than half the length of the lips. Thus a mold

can be passed between the arms of each pair and stably supported by them. Other arms 72 and 73 are secured to the uprights near their bottom ends and support troughs 74 and 75 beneath the locations of the molds to catch water dripping from them.

In operation the temperature of the wax in the supply kettle or tank 1 is maintained at a temperature preferably about 10° higher than the melting point of the wax; that is, as nearly as feasible the lowest temperature at which it will flow freely. And the water is supplied to the cooling tank at a temperature enough lower than the melting point to insure that the wax will be solidified by the time the molds reach the discharge end. The water inlet 10 to the tank is at the rear end and the outlet 11 at the front end, wherefore the flow of water is counter to the travel of the molds and the wax is subjected to continuously lower temperatures as it loses heat. The length of the tank, rate of progress of the molds from front to rear ends thereof, and rate of admission of water are all factors having an influence on the temperature at which water is supplied. And of course the entering water must be considerably cooler than the melting temperature of the wax. I have found in practice that water supplied at 60° F. is cool enough to serve the purpose with the apparatus on which the showing of the present disclosure is based. But this is not a critical temperature.

The operator at the front or head end fills the molds, places them in the tank one by one, and moves the pusher back and forth after so placing each mold. The operator at the rear or foot end removes the mold at the end of the line nearest to him as soon as it drops from the shoulder 36; inverts the mold; raises the plug 28 out of the vent hole 27 and shifts it to one side; passes the mold through the bottom opening 38 of the extractor chamber until arrested by the centering bar 55 and brings the supporting arms 41 and 42 under the lips of the mold; opens and closes the valve of the steam nozzle 58; and then, after the wax slab has fallen free, spreads open the supporting arms and allows the mold to fall out. These actions of the rear end operator are performed during the time required for the other operator to fill a mold with molten wax, place it in the tank, and operate the pusher. With the molds of the apparatus here illustrated, having internal dimensions of 18" high by 12" wide by 1 $\frac{3}{8}$ " (average) thick, the time devoted to filling is at least thirty seconds (to avoid foaming) and the total handling time about one minute. Thus the output of slabs of these dimensions is at least sixty per hour.

What I claim and desire to secure by Letters Patent is:

1. In a slab casting apparatus of the character set forth, a mold having side walls completely surrounding an interior space, a closed bottom end and an open upper end, with flanges at opposite sides of its open end, each flange projecting away from the other, and a pin extending downward from one of said flanges, the other flange having a hole, said pin and hole being at equal distances from corresponding ends of the respective flanges.
2. In a slab casting apparatus of the character set forth, a mold having side walls completely surrounding an interior space, a closed bottom end and an open upper end, with flanges projecting outwardly from the upper edges of its opposite side walls, a pin extending downward from one

of said flanges, the other flange having a hole, said pin and hole being at equal distances from corresponding ends of the respective flanges, and outwardly flaring wings at the ends of said flanges having terminal lips adapted to suspend the mold from supporting means.

3. The mold set forth in claim 2, having a vent opening in its bottom wall, a plug adapted to enter and close said vent opening, and a resilient arm pivoted to the outside of said bottom wall to which the plug is secured, said arm being shiftable to locate the plug in registry with the opening and at one side thereof, and its resilience causing the plug to enter the opening when registered therewith, and permitting withdrawal from the opening.

4. In a slab casting apparatus of the character set forth, a tank having side and end walls and being open at the top, track elements mounted on the top edges of the opposite side walls of the tank, and guard rails extending lengthwise of the tracks and overlying them in spaced apart relation, combined with molds having lips at opposite sides of their upper ends projecting outwardly to an extent enabling them to rest on the tracks at opposite sides of the tank beneath the adjacent guard rails, and being disposed to suspend the molds into the interior of the tank, said molds having flanges at intermediate sides of the upper end extending oppositely to one another, one of said flanges having a downwardly extending pin and the other having a hole, said flanges and the pins and holes of the several molds being so disposed that the pin carrying flange of each mold is enabled to overlap the hole-containing flange of the adjacent mold and the pin carried by the overlapping flange to enter the hole in the underlying flange when a series of molds are so suspended in the tank.

5. In a slab casting apparatus according to claim 4, the tank formed with a downward jog in the top edges of its side walls adjacent to the rear end and at a distance from the rear end wall enough greater than the distance between outer edges of the flanges of the molds to permit descent of the rearmost mold of a series of molds suspended in the tank, and disengagement thereof from the pin of the next following mold, when 10 said rearmost mold is near the rear end wall of the tank.
